NONREFILLABLE CHARRED WOOD LIQUOR BOTTLE

Johnny Costello, Represa, Calif.

Application April 8, 1935, Serial No. 15,303

3 Claims. (Cl. 217—6)

My invention relates to improvements in non-refillable charred wood liquor bottles, and it consists of the combinations, constructions and arrangements hereinafter described and claimed.

5 An object of my invention is to provide a non-refillable charred wood liquor bottle which is preferably made of wood such as oak, or other suitable wood, and which has its interior charred so that the liquor will be surrounded by a charcoal 5 lining.

10 The bottle is formed of various pieces. The four sides of the bottle are made of four separate pieces, and these are joined together by tongue and grooves and the joints are cemented. The 15 top of the bottle is formed of a single piece, and this top includes a neck and shoulders, the shoulders fitting down over the four sides. The neck has a closed top and the interior of the neck is bored out for receiving a cork. A portion of the 20 exterior surface of the neck has a groove and when the bottle is opened it is necessary to cut along this groove, whereupon the top is severed from the shoulders at the weakened groove and the cork is thereafter used as a stopper. This 25 prevents the bottle from being refilled without detection.

In filling the bottle at the factory, the bottle is inverted, and then filled, after which the bottom is placed in position and is cemented to the side 30 walls.

35 Although the device is designed primarily for holding liquor it is obvious that the bottle may be filled with other ingredients and that the interior of the bottle need not be provided with a charcoal lining if this is not needed.

Other objects and advantages will appear in the following specification, and the novel features of the device will be particularly pointed out in the appended claims.

40 My invention is illustrated in the accompanying drawing forming a part of this application, in which

Figure 1 is a side elevation of the bottle shown partly in section;

45 Figure 2 is a front elevation of the bottle also shown partly in section; and

Figure 3 is a horizontal section through the four walls of the bottle.

In carrying out my invention I provide a bottle 50 in which the walls are formed from four different pieces of wood. In Figure 3 I show a front wall 1, side walls 2 and 3, and a rear wall 4. These walls may be joined to each other in any desired manner, and I have indicated the front 55 wall as having grooves 5 and 6, and the rear wall

as having grooves 7 and 8. The side wall has tongues 9 and 10 which are received in the grooves 5 and 7, while the side wall 3 has tongues 11 and 12 which are received in the grooves 6 and 8. The parts are cemented when assembled and the result is a water-tight joining.

Figure 3 also shows the interior surfaces of the four walls as being provided with a charcoal lining 13. This lining can be formed on the surfaces in any manner desired, and may be provided prior to the joining together of the four walls, or after the four walls have been joined together.

In order to make the bottle non-refillable I provide a top, neck and shoulder portion which is turned in one piece. The top 14 is integral with the neck 15 and may be shaped to resemble the standard bottle. The neck in turn is integral with the shoulders 16, and the latter fit down upon the upper edges of the walls 1 to 4 inclusive. If desired, the front and back walls 1 and 4 may be higher than the side walls. In the drawing, however, I have shown the four walls all of the same height, although I do not wish to be confined to this particular construction.

The front and back walls 1 and 4 have their upper edges formed to make a half-lap joint 17 with the front and rear walls of the shoulder portion 16, see Figure 1. In Figure 2 I show the manner of joining the side walls 2 and 3 with the shoulders 16. This joining is in the nature of a tongue and groove joint 18. The half-lap joints 17 and the tongue and groove joints 18 are cemented to the walls 1 to 4 inclusive, and the bottle is now provided with a closed top and four walls which will hold a liquid.

The interior of the shoulder portion 16 is provided with a charcoal lining 19. The neck 15 has a recess 20 formed therein with an enlarged portion 21. The head 22 of a cork 23 is received in the enlarged portion 21, while the body of the cork extends into the recess 20. The cork is inserted from the inside of the shoulder portion and in the partly sectional views of Figures 1 and 2, is shown in elevation.

The neck 15 is weakened adjacent to the head 22 of the cork, and this is accomplished by forming a groove 24 in the neck. The groove is disposed opposite to the enlarged portion 21 of the recess, and this makes the wood at this portion very thin.

The bottle is turned upside down when being filled, and after it is filled a bottom piece 25 is disposed in place. The bottom piece 25 has a marginal groove 26, which receives the four sides 55

1 to 4 inclusive, and the bottom also has a central portion 27 defined by the marginal groove 26, and this central portion enters the bottle a slight distance. The place of joining between the bottom and the walls is cemented and the bottle is now completed. The inner surface of the bottom 25 is provided with a charcoal lining 28.

The front face of the front wall 1 may be provided with a depressed surface 29 if desired in order to cause the bottle to resemble a standard glass liquor bottle. A label may be applied to the bottle, if desired. In opening the bottle a knife is used for cutting the neck at the weakened groove 24, and this will sever the top 14 from the neck 15. The cork 23 is now exposed and may be removed for pouring the contents from the bottle. The cork can be used for closing the bottle and will protect the portion of the contents remaining in the bottle.

It will be clear that the bottle is mutilated when the top 14 is removed, and this will prevent the bottle from being used again.

While I have shown only the preferred form of my invention, it should be understood that various changes or modifications may be made within the scope of the appended claims without departing from the spirit of the invention.

I claim:

1. A non-refillable wood bottle including a neck portion with a closed top and a groove in

the outer surface of the neck, said neck having a recess for receiving a stopper from the inside of the bottle, and a stopper in the neck portion, the recess having an enlargement disposed adjacent to the groove, said stopper having a head receivable in the enlargement.

2. A non-refillable bottle made of wood comprising a one piece neck and shoulder portion, the neck having a closed top, four side walls having joints connecting them to the shoulder portion and to each other, and a bottom securable to the side walls after the bottle has been filled, said neck having a stopper receiving recess with an enlargement for receiving the enlarged head of the stopper, a stopper in the recess and having a head disposed in the enlargement, said neck having a groove in its outer surface disposed adjacent to the enlargement.

3. A liquor bottle made of wood and comprising four flat sides cemented together and forming a body portion for the bottle rectangular in cross section, a shoulder and neck portion provided with a closed top, the shoulder portion being cemented to the four sides, a cork placed in the neck portion on the inside of the bottle, and a bottom cemented to the four walls, the neck being provided with a weakened portion adjacent to the top of the cork.
